UNITED STATES PATENT OFFICE.

LEE LA TOUR AND ALTON F. MUNNELL, OF OMAHA, NEBRASKA, ASSIGNEES TO
PROGRESS ROLLER COMPANY, OF OMAHA, NEBRASKA, A CORPORATION.

APPARATUS FOR FORMING INKING ROLLERS.

1,420,849.

Specification of Letters Patent. Patented June 27, 1922.

Application filed January 20, 1921. Serial No. 438,802.

To all whom it may concern:

Be it known that LEE LA TOUR and ALTON F. MUNNELL, citizens of the United States, residing at Omaha, in the county of Douglas 5 and State of Nebraska, have invented certain new and useful Improvements in Apparatus for Forming Inking Rollers, of which the following is a specification.

This invention relates to apparatus for 10 forming rubber inking rollers having a greater elasticity or yielding quality than ordinary, and consists of the novel combination and arrangement of parts described herein and claimed.

15 The invention is described in connection with a drawing wherein Fig. 1 is a view, partly in section, of an inking roller and parts connected therewith which are used in its formation. Fig. 2 is a side view of an 20 apertured disc. Fig. 3 is a transverse section on line 3—3 of Fig. 1. Fig. 4 is a side view of a molding-rod. Fig. 5 is a side view of a completed inking-roller. Fig. 6 is an 25 end view of the same.

Numeral 1 indicates a shaft having a suitable diameter and length for the inking-roller 2, the latter having a series of longitudinal apertures 3', best shown in Fig. 6, extending entirely therethrough, said apertures being approximately equidistant from 30 each other and at uniform distances from and near to the shaft, said roller also having apertures 4' similar to but at greater radial distances from the shaft, each aperture 4' 35 being disposed in a plane between the radii of two adjacent apertures 3'; and while only two series of apertures 3' and 4' are shown for an inking-roller, any desired number of series of apertures may be formed.

40 At 5 are indicated a pair of discs, each being provided near its central aperture α with a series of apertures 3, and outwardly of its apertures 3 is provided with a series of apertures 4, the apertures of each series being 45 disposed at uniform distances from each other, and the apertures 4 being disposed in a plane, radially considered, midway between two adjacent apertures 3. In making an inking-roller, adhesive material is first 50 applied to the shaft, and after the pair of discs 5 have been placed on the shaft inwardly of the ends thereof, a sheet 6 of india rubber is placed and rolled upon that part

of the shaft between the discs, the amount of rubber thus wound upon the shaft being such 55 that it will lie closely adjacent to the inner series of apertures 3.

Rods 7 are then inserted in the apertures 3 of the discs to lie upon the rubber windings, said rods first being coated with water-glass soap or similar material to prevent 60 adhesion thereof to the rubber, the rods being of such length that they will protrude outwardly of the discs; the sheet rubber is then wound upon to lie between the discs 65 outwardly of the molding-rods 7, the amount of rubber thus wound being such that it will lie adjacent to the apertures 4 of the discs. Molding-rods 8, similar to the rods 7, are 70 then inserted in the apertures 4 of the discs to lie upon the rubber sheets thus wound; and rolling of the rubber sheet is then continued until the space between the discs is 75 filled, the diameter being equal to the diameter of the discs.

The rubber thus prepared is inserted in a tubular mold 9, the cylindrical surface of the rubber first being coated with water-glass soap or similar material so that it may be conveniently removed from the mold. 80 The discs 5 are then pressed toward each other by any suitable means, the means herein shown for this purpose being a pair of clamping-bars 10 having sleeves 11 for receiving the protruding ends of the shaft, the 85 ends of the bars 10 being apertured for receiving a pair of bolts 12. By rotating the keepers or nuts b which are threaded on the bolts, the bars 10 may be pressed toward each other for compressing the rubber within the 90 mold.

The mold and contents are then subjected to heat ranging from approximately 270 to 290 degrees F., and thereafter the molding-rods 7 and 8 may be removed, and the roller 95 removed from the mold, the result being that the inking-roller will have a smooth surface ready for use, its series of apertures 3' and 4' causing a yielding effect and lesser resistance when in use, than ordinary.

100 While india rubber has been mentioned as a material used in constructing inking rollers, other similar material could probably be substituted; also it is obvious that various kinds of resilient rollers, for different purposes, may be made by use of the

means described, and we do not wish to be understood as limiting the invention specifically to inking rollers.

We claim:

- 5 1. In resilient-roller forming means, a tubular mold, a pair of adjacently disposed discs in the mold each having a central aperture and having a series of apertures disposed at uniform distances from each other
- 10 10 equidistant from the central aperture and having a second series of apertures disposed at uniform distances from each other outwardly of and in radial planes midway between the apertures of the first named series,
- 15 15 a shaft engaging in the central apertures and projecting outwardly of the discs, a series of molding-rods engaging in the apertures of the first named series and projecting outwardly of the discs, a second series of molding-rods engaging in the apertures of the
- 20 20 second series and projecting outwardly of

the discs, and means for moving the discs toward each other.

2. In resilient-roller forming means, a tubular mold, a pair of discs in the mold 25 each having a main central aperture and a series of secondary apertures outwardly of the central apertures, a shaft removably mounted in the central apertures and projecting outwardly of the discs, molding-rods 30 removably mounted in the secondary apertures and projecting outwardly of said discs, and means for moving the discs toward each other.

In testimony whereof, we have affixed our 35 signatures in presence of two witnesses.

LEE LA TOUR.
ALTON F. MUNNELL.
